UNITED STATES PATENT OFFICE.

LOU L. LAWLESS, OF TOMAHAWK, WISCONSIN.

RAILROAD-CROSSING SIGNAL GATE.

Application filed September 3, 1921. Serial No. 498,205.

To all whom it may concern:

Be it known that I, LOU L. LAWLESS, a citizen of the United States, residing at Tomahawk, in the county of Lincoln and 5 State of Wisconsin, have invented certain new and useful Improvements in Railroad-Crossing Signal Gates, of which the following is a specification, reference being had to the accompanying drawings.

10 It is the purpose of the present invention to provide a crossing signal for railroads, adapted to be actuated by the tread of the car wheels, so as to throw the signal proper in the path of the road crossing, for the purpose of signaling to automobiles that a train 15 is approaching.

Another purpose is to provide a signal apparatus of this kind including a trip on the side of the rails, for actuating a pneumatic 20 pump, which forces air into a second cylinder, to actuate a piston, whereby a tilting or semaphore arm may be operated, so as to lower a gate signal on one side of the road where it can be seen by a chauffeur of an 25 automobile.

Still another purpose is the provision of a trip for actuating the gate signal when the train is going in one direction, and when the train is travelling in the opposite direction 30 the trip will move from one side by engagement with the wheels.

While the design and construction at present illustrated and set forth are deemed preferable, it is obvious that as a result of a 35 reduction of the invention to a more practical form for commercial purposes, the invention may be susceptible of changes, and the right to these changes is claimed, provided they are comprehended within the 40 scope of what is claimed.

The invention comprises further features and combination of parts, as will be herein-after set forth, shown in the drawings and claimed.

45 In the drawings:

Figure 1 is a plan view of the improved signal and crossing gate constructed in accordance with the invention and showing the same applied to a railroad track;

50 Figure 2 is a view in side elevation of the same, showing the pneumatic cylinders in section and the signal gate lowered;

Figure 3 is an enlarged plan view of the actuating trip to be operated by the car 55 wheels;

Figure 4 is a view in side elevation of the trip shown in Figure 3;

Figure 5 is a sectional view on line 5—5 of Figure 3;

Figure 6 is a sectional view of the release 60 valve 47; and

Figure 7 is a diagrammatic plan view of the crossing signal gate as applied to the side of a track, where a single track may be used, showing an actuating device for the 65 signal gate in a position on either side of the crossing, approaching the same from either direction.

Referring to the drawings, 1 designates a track, and 2 the ties thereof, and 3 and 4 70 are uprights, which are mounted upon certain of the ties of the track.

Secured to the upright 3 by means of suitable supports 5 is a pneumatic cylinder or pump 6, which includes a suitable piston 7 75 therein provided with a leather washer 8, for wiping against the walls of the cylinder. The piston 7 is carried by a piston rod 9, which operates through one end of the cylinder 6. It is obvious that the cylinder 80 6 may be disposed so that it may operate in an upright or horizontal position.

Mounted in suitable bearings 10 of one of the ties is a crank shaft 11, one arm 12 of which is pivotally connected by means of a 85 pin 13, which engages through a slot in the arm 12.

The other arm 14 lies adjacent the outer portion of the rail and beneath a trip 15. The trip 15 is disposed adjacent the side of the rail, there being a bolt 16 passing through the rail and through one end of the trip. Plates 17 and 18 are mounted on one end of the bolt, and disposed between the plate 17 and the trip is a heavy coil spring 90 19. These plates 17 and 18 have interengaging 95 arcuate faces 20, there being a nut 21 threaded upon the bolt, for increasing or decreasing the tension of the spring. One end of the trip 15 has an elongated opening or slot 22, through which a bolt 23 engages.

This bolt also engages through one of the rails, and threaded to one end of the bolt is a nut 24, to engage a shoulder 25, where the reduced end of the bolt connects with the body of the bolt. By means of this bolt the trip is limited in its movement. The trip at one end is beveled off at 26, and has its upper face inclined downwardly toward the ball of the rail, so that a train approaching in the direction of the arrow *a*, will cause the 100 105 110

trip to depress, due to the tread of the wheels engaging with the upper surface of the trip. The inner portion of the trip for a distance from the bolt 23 to the other end of the trip 5 is recessed longitudinally, and the vertical wall of this recess inclines at an acute angle to the side of the ball of the rail, so that when a train is passing in the direction of the arrow *b*, the tread of the wheels will ride against the inclined surface 27 and move the trip laterally, thereby not affecting the crank shaft. However when the train is moving in the direction of the arrow *a*, the tread of the wheels will ride upon the trip, 10 and thereby rock the crank shaft 11, causing the piston 7 to move in its cylinder against the action of the spring 29, therefore forcing air through the pipe 30 into the pneumatic cylinder 31.

20 Mounted in the cylinder 31 is a piston 32 which comprises a body 33, a follower plate 34 and the usual leather 35, there being an expanding spring 36 for the leather, to prevent the escape of air under pressure into 25 the space above the piston. The cylinder 31 is mounted upon the support 4, which rises from one of the ties of the track, and carried by the piston is a piston rod 38. A link 39 is connected to the rod 38, and in 30 turn to a rocking gate or semaphore arm 40 as at 41. The arm or lever 40 is pivotally mounted at 42 on the support 4. The shorter end of the gate arm carries a weight 43, while a suitable signal 44 is pivotally 35 mounted at 45 on the longer end of the gate arm. This signal when lowered is design to be in a position so as to be readily seen or observed by the driver or chauffeur of a vehicle, when approaching the railroad 40 crossing, when the apparatus has been operated by a train for lowering the signal. The pipe 30 is provided with a conventional 45 form of check valve 46, to prevent the pressure of air through the pipe from returning to the cylinder 6.

The cylinder 6 and the trip are designed to be arranged a substantial distance from the crossing, so that the trip may be actuated by the wheels of the train a considerable 50 time before the train reaches the actual crossing, so that the signal may be disclosed to the chauffeur or driver of the approaching vehicle sufficiently to prevent the vehicle from reaching and attempting to cross 55 the track before or at the time the train arrives at the crossing.

The pipe 30 is provided with a suitable release valve 47, there being an actuating arm 47^a connected to the stem of the release valve, 60 so as to be engaged by the car wheels, for the purpose of releasing the air and allowing the piston 32 to restore to its normal position, and raise the signal to its initial position, just immediately before or at the time 65 the engine of the train reaches the crossing.

The semaphore arm has a contact 48 to engage a contact 49. The contacts 48 and 49 are in circuit with a suitable bell 50, a lamp 51 and battery 52, by virtue of the wires 53, so that when the semaphore arm is tilted to 70 lower the signal the bell will be actuated, and the lamp lighted, so as to notify the chauffeur or driver of an approaching vehicle when a train is approaching the crossing. The lamp 51 may be located any suitable 75 place, preferably on the gate arm 40. While the signal 44 is of the form shown in the drawings, it is obvious that any form of signal may be employed. While compressed air is used for actuating the pistons in the cylinder 31, it is obvious that vacuum may be employed for performing the same function. In this case, the arrangement of parts 80 may be changed.

85 The signal 44 is provided with a suitable mirror 44^a, upon which the light rays from the headlight of an automobile may be reflected from either side of the crossing.

It will be noted that Figure 7 discloses a 90 diagrammatic arrangement of the pneumatic actuating means, so that the crossing signal gate may be actuated when a train is approaching the crossing from either direction. For this reason it is necessary that the trip be constructed in order that it may be 95 deflected from the side of the rail, after a train has passed the crossing going in either direction. For instance when a train is approaching the crossing in the direction of the arrow *c* in Figure 7, the trip is actuated, 100 thereby causing the piston in the pneumatic cylinder 6 to force air through the pipe 30, so as to actuate the piston in the cylinder 31, and when the train reaches the arm or lever 47^a, the flanges of the car wheel 105 will engage with the arm 47^a and open the release valve 47. When the train reaches the trip 15 on the other side of the crossing, the trip will be deflected from the side of the rail, thereby preventing the piston of the 110 cylinder on the opposite side of the crossing from being actuated. In view of the track in Figure 7 being single, a train passing in the opposite direction will likewise operate the signal gate.

115 The invention having been set forth, what is claimed as being useful is:

1. The combination with a railroad crossing, of a signal arm provided with a signal to assume a position at the crossing, whereby 120 it may be observed by the driver of the vehicle when the arm is tilted, a crank shaft arranged adjacent the side of the railroad track, a car wheel actuated trip for engaging with one arm of the crank shaft for 125 rocking the same, said trip having a raised portion at a point between its ends protruding above the surface of the rail, the upper surface of the trip being beveled in opposite directions from the raised portion toward 130

- the opposite ends of the trip, whereby the car wheels may depress one end of the trip, yieldable means for holding the trip adjacent the side of the rail, the inner portion of 5 the trip adjacent the rail having an elongated cut away portion of right angle in cross section, one wall of said cut away portion being inclined toward the rail, whereby the car wheels may engage therewith and 10 cause movement of the trip away from the side of the rail without depressing the same, and means operatively connecting the crank shaft and the arm for tilting the same to lower the signal.
- 15 2. The combination with a railroad crossing, of a signal arm provided with a signal to assume a lowered position at the crossing when the arm is tilted, a pivot projecting laterally from the side of the rail, a trip 20 loosely mounted on the pivot adjacent the side of the rail, means on the pivot to bear against the trip and hold it flat against the side of the rail, a guide on the side of the rail upon which the trip is loosely guided, a 25 member to be actuated by the trip when actuated by the car wheels, and being operatively connected with the arm for tilting it and lowering the signal at the crossing, the inner side portion of the trip having a bevel 30 inclined toward the side of the rail against which the car wheels cam, to force the trip outwardly against the action of the means on the pivot when the car wheels are traveling in one direction.
- 35 3. The combination with a railroad crossing, of a signal arm provided with a signal to assume a lowered position at the crossing when the arm is tilted, a lateral pivot carried by the side of the rail, a trip loosely 40 mounted upon the pivot and lying adjacent the side of the rail, yieldable means on the pivot bearing against and holding the trip in position, means at one end of the trip for loosely guiding the trip when depressed, 45 said trip being raised above the surface of the rail whereby the car wheels may depress the same when moving in one direction, means actuated by the trip when depressed and being operatively connected with the 50 arm for tilting the same and lowering the signal at the crossing.
4. The combination with a railroad crossing, of a signal arm provided with a signal to assume a lowered position at the crossing 55 when the arm is tilted, a lateral pivot carried by the side of the rail, a trip loosely mounted upon the pivot and lying adjacent the side of the rail, yieldable means on the pivot bearing against and holding the trip in position, means at one end of the trip for 60 loosely guiding the trip when depressed,
- said trip being raised above the surface of the rail whereby the car wheels may depress the same when moving in one direction, means actuated by the trip when depressed 65 and being operatively connected with the arm for tilting the same and lowering the signal at the crossing, said trip having means to be engaged by the car wheels when moving in the opposite direction to force 70 the trip laterally against its holding means.
5. The combination with a railroad crossing, of a signal arm provided with a signal to assume a lowered position at the crossing 75 when the arm is tilted, a lateral pivot carried by the side of the rail, a trip loosely mounted upon the pivot and lying adjacent the side of the rail, yieldable means on the pivot bearing against and holding the trip 80 in position, means at one end of the trip for loosely guiding the trip when depressed, said trip being raised above the surface of the rail whereby the car wheels may depress the same when moving in one direction, 85 means actuated by the trip when depressed and being pneumatically connected with the arm for tilting the same and lowering the signal at the crossing, said trip having means to be engaged by the car wheels when 90 moving in the opposite direction to force the trip laterally against its holding means, and means actuated by the car wheels for releasing the pressure of the pneumatic means, to permit the arm to restore to its 95 initial position and raise the signal.
6. As an article of manufacture, a track trip for actuating a signal arm, comprising a crank shaft arranged adjacent the side of a railroad track and provided with a crank 100 arm, a car wheel actuated trip for engaging said arm for rocking the shaft, said trip having a recessed portion at a point between its ends protruding above the surface of the rail, the upper surface of the trip being 105 beveled in the opposite directions from the raised portion toward the opposite ends of the trip, whereby the car wheels may depress one end of the trip, yieldable means for holding the trip adjacent the side of the 110 rail, the inner portion of the trip adjacent the rail having a rabbet, the perpendicular wall of the rabbet being inclined toward the side of the ball of the rail, whereby the car wheels may engage therewith and cause 115 movement of the trip away from the side of the rail without depressing the same, and means connecting the crank shaft and the signal arm.

In testimony whereof I hereunto affix my 120 signature.

LOU L. LAWLESS.
